UNITED STATES PATENT OFFICE

PAUL DEVAUX, OF JUVISY, FRANCE

DRIVING MEANS FOR THE ROLLERS OF SPINNING MACHINES

Application filed May 14, 1929, Serial No. 362,894, and in France March 30, 1929.

The invention relates to drawing arrangements for preparing and spinning machines in the spinning of cotton, wool and the like, and more particularly to improved driving means for rollers of small diameter.

In the spinning of cotton, wool and the like, experience shows that a better output of the machines can be obtained if the fibres are controlled and guided, at a given speed, to a point located as close as possible to the nip of the drawing rollers, that is, constructively, by approaching as much as possible the nips of two consecutive pairs of rollers.

15 The present invention has for its object to provide improved means for conveniently driving rollers of such small size so that the nips of two consecutive pairs of rollers may be brought as close together as desired, while 20 providing for the necessary strength of such rollers.

The invention has further for its object to keep the advantages of the rollers heretofore employed, and to obviate their respective 25 drawbacks.

According to the invention, the small roller or rollers, which is or are to be actuated, are made of a magnetic substance, and rest upon a driving shaft which may have the 30 normal diameter of the rollers of spinning machines, and is driven at one end or in any other suitable manner, the positive drive of said small roller or rollers at the proper speed being secured magnetically by means 35 of a magnetic field which is caused to pass through said small roller or rollers.

The small roller or rollers thus have the small diameter which is necessary to allow 40 them to approach as much as desired the adjacent pair of rollers. To provide for the proper strength, the rollers may be formed into short sections or are suitably supported upon their whole length.

In a convenient embodiment of the invention, the magnetic field is produced by one 45 or more permanent magnets of any suitable shape and diameter, mounted on the driving shaft and rotated thereby.

Further features of the invention will be 50 specified in the following description, with

reference to the accompanying drawings, which are given solely by way of example, and show various embodiments of the invention.

Figure 1 is a cross-section of a drawing 55 mechanism showing the improved driving means for small rollers, embodying cylindrical permanent magnets mounted on a driving shaft.

Figure 2 is an elevational view of the driving shaft to which is secured a cylindrical permanent magnet, which supports and drives a small fluted roller, upon which rests a pressure roller.

Figure 2^a illustrates a modification of the 65 arrangement shown in Figure 2, in which the magnets have the shape of sleeves.

Figure 3 shows diagrammatically a modification of Figure 1.

Figure 4 is an elevational view of the 70 permanent magnet shown in Figure 2.

Figure 4^a is a cross-section on the line 4^a—4^a of Figure 4.

Referring to Figure 1, 1 and 1^a are the usual drawing rollers, 7 and 7^a the usual intermediate rollers, and 8 and 8^a the usual feed rollers, of a drawing mechanism of a known spinning frame or preparing machine.

To control and guide the fibres of the 80 rove or sliver to a point situated as close as possible to the nip of the drawing rollers, the mechanism comprises a pair of rollers 2 and 9 of a very small diameter (say 8 millimeters) whereby the nip of rollers 2 and 9 is very close to the nip of the drawing rollers 1, 1^a.

As above mentioned, it is practically impossible to drive the roller 2 at one end of the machine, as in the case of rollers of 90 standard size, by reason of the small diameter and great length of such a roller.

According to the invention, roller 2 is positively driven at the proper speed, without torsion or flexion, by means of a driving 95 shaft 3 having the normal diameter of the rollers used in spinning machines, and upon which said roller 2 is adapted to rest, the positive connection between roller 2 and shaft 3 being secured by the mutual attraction pro-

duced by a magnetic field traversing roller 2, which, for this purpose, is made of a magnetic substance.

In a convenient form of the apparatus, the 5 magnetic field is produced by permanent magnets forming cylindrical bearings supporting roller 2, said bearings positively driving roller 2 by the combined effect of the friction and the molecular attraction, 10 thus obviating any slipping.

As shown in Figures 2 and 4, the permanent magnet 4 may consist of two sleeves 10 and 11, connected together by a cross-member 5, thus forming a kind of horseshoe magnet 15 having cylindrical pole-pieces, and whose field is distributed upon the peripheral surfaces *a* and *b* of said pole-pieces (Fig. 4).

Efficient magnets may be more readily made of simple sleeves 12 and 13 (Figure 2^a), 20 deprived of the cross-member 5, each sleeve thus forming a separate permanent magnet.

Magnets 4 (Figures 1, 2, 4) or sleeves 12 and 13 (Figure 2^a) are shifted on the driving shaft 3, and are rotated thereby at the 25 proper speed.

These improved driving means permit to reduce the diameter of roller 2 to a minimum. For instance, with a diameter of 9 millimeters for roller 2 and of 22 millimeters for 30 roller 1, the spacing between the nips of the two pairs of rollers 1-1^a and 2-9 is reduced to 15 millimeters.

With a roller 1 of larger diameter, the diameter of roller 2 may be reduced in order to 35 preserve the same spacing. For instance, with a diameter of 25 millimeters for roller 1, and 8 millimeters for roller 2, the spacing between the nips of the two pairs of rollers 1-1^a and 2-9 is still 15 millimeters, while 40 providing between said rollers the necessary clearance.

Rollers 2 are preferably made of sections whose length is proportionated to their diameter, so as to secure the necessary strength.

45 According to the length of said rollers, these may be supported by the stand for the usual lower rollers (Figure 1), with the interposition of smooth bearings, ball bearings, or the like. They may also be supported by 50 the lower part of the slides, or caps, which supports the usual upper rollers.

The driving shaft 3 may be supported by the usual stand or in any other manner. As above indicated, said shaft has the standard 55 diameter for a lower supporting roller, for instance 13 millimeters in the case where the upper roller 9 rests by its own weight, or a greater diameter in the case of a weighted pressure roller. Shaft 3 may be made of sections carrying male and female coupling members at their ends, as in the usual rollers employed in spinning machines.

60 Shaft 3 may thus be driven at its end by a gearing, and it will obviously be rotated in 65 the contrary direction to rollers 1, so as to

rotate roller 2 in the direction of travel of the rove or sliver, that is rollers 2 and 9 will rotate according to the arrows *f*₁ and *f*₂ (Figure 1).

Roller 2 may be smooth upon its whole 70 length, as well as the pole-pieces 10-11-12-13.

Shaft 3 may support and actuate several 75 rollers such as 2. For instance, in Fig. 2, a shaft 3 carries two rollers 2 and 14, and a shaft 3^a carries two rollers 15, 16. The number of rollers such as 2 may be increased if necessary, and said rollers may have equal or unequal diameters, and be imparted the same or different peripheral speeds. 80

In this latter case, it is possible to impart to rollers 2 different peripheral speeds, due to the differences between the diameters of the parts or journals resting on the magnets and the fluted parts carrying the sliver. 85

As shown by way of example in Figures 2 and 2^a, the width of each pole-piece 10-11, or each magnet 12-13 is somewhat less than the width of the smooth journals of roller 2.

If the rollers 2, 14, 15, 16 have different 90 diameters at their journals above the magnets and at the fluted parts carrying the rove, the cross-members 5 connecting the pole-pieces of magnets 4 must be recessed, as shown at 6.

The magnets are secured to shafts 3-3^a 95 by any suitable means such as screws, keys, hoops, clamping, pressing or the like; they are preferably insulated magnetically from shaft 3, for instance by brass tubes or linings when shaft 3 is made of steel. 100

The cross-members 5 (Fig. 4) of the successive magnets 4 are preferably spaced angularly with respect to one another, in order that a single cross-member 5 be located on a given generatrix of shaft 3 and be in 105 contact with roller 2, the external magnetic field being somewhat weaker adjacent these parts 5 of magnets 4.

Due to the elimination of the cross-members 5, sleeves 12-13 or the like (Figure 2^a) 110 permit greater differences between the diameters of the journals and the fluted parts of rollers 2, 14, 15, 16; they may be more readily distributed along the driving shafts, inasmuch as they may be provided in odd number 115 for a given shaft section, whereas the pole-pieces 10 and 11 of the magnets 4 must necessarily be provided in pairs.

Stationary permanent magnets may be placed in contact with or adjacent to the movable magnets, so as to increase the magnetic field in case a high power is required. Stationary permanent magnets may even be exclusively employed, and these will serve to magnetize suitable sleeves, disks or the like, 120 having any shape and diameter and secured to shafts 3 and 3^a.

The stationary permanent magnets, substituted for the movable permanent magnets, 125 may also assure the adhesion between the 130

driving shafts and the rollers 2, 14, 15, 16 by directly magnetizing the latter; more generally, a magnetic attraction may be substituted for the usual weighted pressures, which represent a certain friction to be overcome.

6 Electro-magnets can also be substituted for and combined with permanent magnets.

It will be noted that the magnetic circuit of the permanent magnets is continually 10 closed by roller 2 or the like, and hence, the magnets will not lose their magnetic force.

15 The aforesaid devices and the modifications above contemplated may be fitted to the existing machines for preparing and spinning cotton, wool or the like, or to machines to be constructed.

20 As above stated, the arrangement may comprise one or more units such as 2, 2, 9 in series, these being substituted for, or combined with the usual rollers. For instance, in Figure 3, and solely by way of example, the pair of intermediate rollers 7 and 7^a is preserved, and the apparatus comprises a set of four pairs of rollers 2, 9—14, 17—15, 18—16, 25 19; the upper rollers 9, 17, 18, 19 rest upon the lower rollers 2, 14, 15, 16 whereof the first two are driven by a shaft 3 and the other two by a like shaft 3^a, by means of magnets such as 4, 12 and 13; it is obvious that all 30 desired combinations of rollers can be provided by adding or eliminating certain rollers. It has also been supposed that the peripheral speed increases progressively from the roller 16 to the roller 2, so as to 35 effect the progressive drawing of the rove between the feed rollers 8, 8^a and the drawing rollers 1, 1^a.

40 Obviously, the invention is not limited to the constructional forms herein described and represented, these being given solely by way of example, and numerous modifications may be made without departing from the scope of the invention.

45 Having now described my invention what I claim as new and desire to secure by Letters Patent is:

1. In a drawing mechanism for textile fibres, a pair of drawing rollers, a driving shaft close to the lower drawing roller, magnets on said shaft and rotatable therewith, a 50 small roller of magnetic substance resting on said shaft, close to the nip of said drawing rollers, and means for exerting a pressure upon the textile fibres passing over said small roller.

55 2. In a drawing mechanism for textile fibres, a driving shaft, cylindrical magnets on said shaft and rotatable therewith and a roller of magnetic substance bearing on said 60 magnets and adapted to be rotated thereby.

3. With a drawing mechanism for textile fibres, the combination of an additional driving shaft close to the lower drawing roller, magnets on said shaft and rotatable there- 65 with, a small roller of magnetic substance

resting on said shaft, close to the nip of said drawing rollers, and means for exerting a pressure upon the textile fibres passing over said small roller.

4. In a drawing mechanism for textile 70 fibres, a driving shaft, magnetic sleeves shifted on said shaft and rotatable therewith and at least a roller of magnetic substance resting on said sleeves and adapted to be rotated thereby.

75 5. In a drawing mechanism for textile fibres, a driving shaft, magnetic sleeves shifted on said shaft and rotatable therewith, cross members of magnetic material for connecting two adjacent sleeves and a 80 roller of magnetic substance resting on said shaft and adapted to be rotated thereby.

6. In a drawing mechanism for textile 85 fibres, a driving shaft, magnets on said shaft and rotatable therewith, a magnetic insulation between said shaft and said magnets, and at least a roller of magnetic substance resting on said shaft and adapted to be rotated thereby.

7. In a drawing mechanism for textile 90 fibres, a driving shaft, magnetic sleeves shifted on said shaft and rotatable therewith, a brass lining between said shaft and said magnets, and at least a roller of magnetic substance resting on said shaft and adapted to be 95 rotated thereby.

8. In a drawing mechanism for textile 100 fibres, a pair of drawing rollers, a driving shaft close to the lower drawing roller, a small roller of magnetic substance resting on said shaft close to the nip of said drawing rollers, means for producing a magnetic field through said small roller and urging the latter toward said driving shaft and means for exerting a pressure upon the textile fibres 105 passing over said small roller.

In testimony whereof I have signed my name to this specification.

PAUL DEVAUX.
